US00D979193S

(12) **United States Design Patent** (10) **Patent No.:** **US D979,193 S**
Callow et al. (45) **Date of Patent:** **** Feb. 28, 2023**

(54) **SHOE MIDSOLE**

(71) Applicant: **adidas AG**, Herzogenaurach (DE)

(72) Inventors: **Liz Callow**, Herzogenaurach (DE);
Angela Smith, Herzogenaurach (DE);
Zachary Coonrod, Herzogenaurach (DE); **Stuart Reinhardt**, Herzogenaurach (DE)

(73) Assignee: **adidas AG**, Herzogenaurach (DE)

(**) Term: **15 Years**

(21) Appl. No.: **29/813,809**

(22) Filed: **Nov. 1, 2021**

Related U.S. Application Data

(63) Continuation of application No. 29/774,470, filed on Mar. 17, 2021, now Pat. No. Des. 943,895, which is a continuation of application No. 29/697,489, filed on Jul. 9, 2019, now Pat. No. Des. 916,444, which is a continuation of application No. 29/614,532, filed on Aug. 21, 2017, now Pat. No. Des. 855,297.

(57) **CLAIM**

The ornamental design of a shoe midsole, as shown and described.

DESCRIPTION

FIG. 1 is a side view of a shoe midsole.

FIG. 2 is another side view of the shoe midsole of FIG. 1, shown from the opposite side.

FIG. 3 is a perspective view of the shoe midsole of FIG. 1, shown from the same side as FIG. 1.

FIG. 4 is another perspective view of the shoe midsole of FIG. 1, shown from the opposite side as FIG. 1; and, FIG. 5 is a back perspective view of the shoe midsole of FIG. 1.

The portions of the shoe midsole surrounded by dashed lines are unclaimed and form no part of the claimed design. The dashed lines are unclaimed boundaries and form no part of the claimed design.

1 Claim, 5 Drawing Sheets
